UNITED STATES PATENT OFFICE.

THOMAS DUNCAN, OF OAKPARK, ILLINOIS, ASSIGNOR TO THE SIEMENS & HALSKE ELECTRIC COMPANY OF AMERICA, OF CHICAGO, ILLINOIS, A CORPORATION OF ILLINOIS.

ELECTRIC METER.

SPECIFICATION forming part of Letters Patent No. 698,648, dated April 29, 1902.

Application filed May 24, 1899. Serial No. 718,023. (No model.)

To all whom it may concern:

Be it known that I, THOMAS DUNCAN, of Oakpark, in the county of Cook and State of Illinois, have invented certain new and useful 5 Improvements in Electric Meters, (Case No. 51,) of which the following is a specification.

This invention relates, broadly, to improvements in transformers, more particularly of that class which are known in the art as "series" transformers and which are employed for reducing or transforming heavy to lighter alternating currents in a manner analogous to the reduction of high-pressure to low-pressure currents by multiple or parallel trans- 15 formers.

In its further development the invention also relates more specifically to the employment of the improvements before referred to in the production of improved electric meters or 20 measuring instruments for certain classes of work. The use of series transformers in connection with such instruments as a means of measuring the current or energy transmitted in circuits in which the current is very heavy 25 offers many practical advantages, since it is found difficult or impossible to construct ammeters, wattmeters, and the like which will successfully carry currents above one thousand amperes. In the electric furnace, for 30 example, the current used in the production of aluminium, calcium carbid, carborundum, &c., is frequently so great as to practically prohibit the use of instruments which must be connected directly into the circuit, and in 35 all such cases it is therefore imperative that a series transformer be employed to reduce the current to such amount as the meter or measuring instrument will carry with safety. Series transformers as heretofore constructed, 40 however, are not well adapted for use in any situation in which it is necessary that the current changes in the primary and secondary circuits should be always accurately proportional to each other, it being well known that 45 in the present types of such apparatus the current through the secondary increases at a more rapid rate than that through the primary circuit. This renders it impossible to obtain correct results with meters and meas-

uring instruments employing such constructions, since it is necessary to accuracy that the current through the instrument shall always bear a constant ratio to the current in the main circuit which is measured.

A principal object of the invention, therefore, is to provide a transformer of such construction that the secondary current will always be exactly proportional to the current through the primary, no matter what the changes in the latter current.

Further objects of the invention are to provide improved construction in meters and measuring instruments employing such improved transformers and by which currents of any strength may be measured accurately 65 and without difficulty or endangering the instruments employed.

These objects I am enabled to accomplish by reason of the fact which I have experimentally discovered that if the secondary of 70 a series transformer be connected in shunt around its primary a current may be obtained through the secondary circuit which will vary in exact accordance with or bear a constant proportion to the primary or main current. This fact is based upon my precedent discovery that whereas (as is well known and above stated) the current through the secondary of an ordinary series transformer increases more rapidly in proportion than the 80 current through its primary. The current through a circuit shunted around the primary will increase less rapidly than the primary or main current, so that if two such derived circuits be combined the tendency of 85 the current in the one to increase too rapidly will be counteracted by the tendency of the current in the other to increase too slowly, with the resultant effect of a current bearing a constant or straight line ratio to the main 90 current throughout all variations in the latter. This being the case, it is only necessary to connect the field-coil of the meter or measuring instrument in such secondary shunt-circuit in order to obtain accurate readings 95 of the main circuit.

The invention consists in the matters herein set forth, and more particularly pointed out

in the appended claims, and will be fully understood from the following description when read in connection with the accompanying drawings, in which—

- 5 Figure 1 shows a simple arrangement of the primary and secondary circuits in a transformer embodying my invention in one form. Fig. 2 shows the application of my improvements to a wattmeter of the induction-motor type. Fig. 3 shows the improved transformer of Fig. 1 provided with means for adjusting or balancing the circuits to obtain the accurate results desired. Fig. 4 shows a transformer embodying my improvements and conforming more to the type ordinarily employed in practice, the same being used in connection with an integrating wattmeter, as in Fig. 2. Fig. 5 illustrates an application of the improvements to an indicating-ammeter. Fig. 6 illustrates their application in connection with an indicating-wattmeter. Fig. 7 shows another style of transformer provided in connection with a wattmeter in accordance with my invention.
- 25 In said drawings, A designates the transformer-core, herein shown as made annular or in the form of a ring, but which may be of any desired or suitable shape or construction, and B its primary coil, which is wound upon the core A in the usual manner and connected in series in the main circuit, as shown in Fig. 2. The secondary coil C is also wound on the core A in the usual manner, but in accordance with this invention is connected at its 30 terminal c to the ends of the primary coil B, or to the main lead on each side of said primary coil, so that it is shunt around the latter. A field-coil D being then connected in series in this secondary or shunt circuit will 35 be supplied with a current which if the resistance and winding are properly proportioned will vary in exact accordance with the variations in the current through the primary.
- 40 The simple elements thus described are shown alone in Fig. 1 and include all essentials of the broad invention, and a transformer so constructed and connected may be advantageously employed in any situation which requires the reduction of a heavy to a 45 light current varying in fixed ratio to the heavy current. The greatest present demand for such apparatus, however, is in connection with meters and measuring instruments, in which the above requirement is essential to accurate results, as hereinbefore stated. In its further development, therefore, the invention contemplates the application of the novel transformer thus described in the construction and installation of such meters and measuring instruments. This merely involves the employment of the coil D as the series field-coil of the meter, or, in other words, the connection of the field-coil of the meter in the 55 secondary shunt-circuit of the transformer. A construction of this kind is shown in Fig.

2, in which D designates the series field-coil of an integrating wattmeter, E its shunt or volt coil, and F its revolvably-mounted armature, which is set in rotation by the inductive action of the magnetic fields set up by the coils D and E. G indicates the magnetic drag, H the impedance-coil for lagging the phase of the current of the coil E, and I a secondary shunt-coil provided with an adjustable resistance i and applied to adjustably modify the action of the impedance-coil H. J designates the generator; L and L', the main leads; M, the transformer for the shunt or volt circuit of the meter, and N the transformer, which supplies any suitable translating devices O.

Fig. 4 shows a wattmeter installation substantially similar to that just described, except that the transformer core and coils illustrated in this case are of a type more usually employed in practice, the connections and principles of operation being, however, alike in both cases.

Fig. 5 illustrates the invention as applied in connection with an indicating-ammeter P, and Fig. 6 its application in connection with an indicating volt-meter V, in which the shunt-coil V' is mounted to rotate in a familiar manner. An important advantage of the present improvement in all of these applications resides in the possibility of regulating the secondary shunt-current of the transformer to compensate in a large degree for the friction of the parts and to aid in overcoming their inertia in starting. This possibility arises from the resultant nature of the secondary current, it being only necessary to vary the proportions of the windings and resistances in order to vary such current above or below the straight-line ratio. Thus if the secondary coil of the transformer is increased beyond the proportions required for maintaining the resultant current in constant proportion to the main or primary current said resultant current will to this extent have an abnormal rate of increase, tending to compensate for and overcome the friction and inertia, as above stated. An adjustment with this in view is illustrated in Fig. 3, in which a switch c' is provided for the purpose of cutting in or out a greater or less number of convolutions of the secondary coil C, as may be found necessary, and this or an equivalent device may be provided in connection with any of the meters or instruments referred to, if found desirable.

A very practical transformer construction in accordance with my invention is shown in Fig. 7, in which the main lead is simply run through the center of the annular core A of the transformer, so that it forms, in effect, a primary coil consisting of a single loop. The secondary coil is wound upon the core A, as before, being herein shown as insulated from the lead L by a sleeve or sheath l, of non-conducting material, and is connected by terminal clamps at c to the lead L on each side of

the core A. These clamps may be slid along on the leads to stand at any desired distance apart, as suggested by the dotted lines at c², and the resultant secondary current thereby 5 varied to the same end, as by the switch c' of the construction shown in Fig. 3 and hereinbefore described. The meter connections in this case are the same as those previously set forth. Other translating or current-consuming 10 means may be included in the shunt-conductor with the secondary of the transformer, or this secondary circuit may be used for a variety of purposes, and I do not, therefore, wish to be limited to the precise disclosure of 15 the invention herein set forth, as modifications and adaptations thereof may be made without departing from the spirit of my invention.

I claim as my invention—

20 1. The combination with a main circuit, of a transformer having its primary coil connected in series in said main circuit and its secondary coil connected in shunt to its primary coil, and an energizing-coil connected 25 in series in said secondary shunt-circuit.

2. The combination with a series transformer having its secondary connected in shunt to its primary circuit, of a measuring instrument or meter provided with an energizing-coil connected in series in said secondary 30 shunt-circuit.

3. The combination with a main circuit of a transformer having its primary coil connected in series in said main circuit and its 35 secondary coil connected in shunt to its primary coil, an energizing-coil connected in series in the secondary shunt-circuit, and means for adjustably varying the relative proportions of the shunt and secondary coil.

40 4. The combination with a main circuit, of a transformer having its primary coil connected in series in said main circuit and its secondary coil connected in shunt to its primary coil, an energizing-coil connected in series in the secondary shunt-circuit, and means for adjustably varying the length of the 45 secondary coil.

5. The combination with a primary circuit, of means for producing an induced current 50 from the primary current, means for deriving a shunt-current from said primary current, and a meter or measuring instrument energized by the combined action of said induced and shunt currents.

55 6. In a system of distribution, the combination with a source of alternating current, of a winding receiving current therefrom, a second winding inductively related to the first and included in a shunt-circuit about 60 the same, and a meter having a winding in-

cluded in the said shunt, substantially as described.

7. In a system of distribution, the combination with a transformer having its primary of few turns and included serially in the circuit, and having its secondary of a larger 65 number of turns and included in a shunt-circuit of said primary, of a meter having an energizing-winding included in said shunt in series with the secondary, substantially as 70 described.

8. In a system of distribution, the combination with a transformer having its primary of few turns and included serially in the circuit, and having its secondary of a larger 75 number of turns and included in a shunt-circuit of said primary, of a wattmeter having a current field-producing winding included in the shunt-circuit and in series with the secondary, said meter also having a pressure 80 field-winding, substantially as described.

9. In a system of electrical distribution, the combination with a source of alternating current, of a transformer having its primary winding receiving current from the said 85 source, the secondary of the transformer being included in a shunt-conductor about the said primary, and a meter having a winding included in the said shunt-conductor, substantially as described. 90

10. The combination with an inducing-coil, of an induced coil in inductive relation therewith included in shunt about the said inducing-coil, and a wattmeter having one of its windings included in the said shunt-circuit, 95 substantially as described.

11. The combination with a transformer having its secondary included in a shunt-circuit about its primary, of a wattmeter having a winding included in the said shunt-circuit, 100 substantially as described.

12. The combination with an inducing-coil, of an induced coil in inductive relation therewith included in shunt about the said inducing-coil, and a wattmeter having its current-winding included in the said shunt-circuit, 105 substantially as described.

13. The combination with a transformer having its secondary included in a shunt-circuit about its primary, of a wattmeter having its current-winding included in the said shunt-circuit, substantially as described. 110

In testimony that I claim the foregoing as my invention I affix my signature, in presence of two subscribing witnesses, this 18th day of May, A. D. 1899. 115

THOMAS DUNCAN.
